UNITED STATES PATENT OFFICE.

GEORGE W. BLAIR, OF MISHAWAKA, INDIANA, ASSIGNOR TO MISHAWAKA RUBBER & WOOLEN MANUFACTURING COMPANY, OF MISHAWAKA, INDIANA, A CORPORATION OF INDIANA.

LOCK FOR QUICK-OPERATING FASTENERS.

Application filed March 20, 1925. Serial No. 16,959.

My invention relates to quick operating fasteners of the type wherein the edges of the parts which are to be joined together, are each provided with a series of elements 5 which are interlocked with the elements of the other series and released therefrom by movement of a slider or operating member therealong, and my invention has reference more particularly to a locking device for 10 holding the operating member or slider in any position of adjustment so as to prevent accidental shifting of the slider and separation of the connected parts.

Fastening devices of this character do not afford adjustment for connecting the parts in more or less separated relation, and it is often times desirable to interlock the fastening elements only part way throughout their 15 length so that the remaining portions are unconnected and capable of more or less separation. This is particularly desirable in overshoes and footwear, as it is impracticable to furnish such footwear in sizes to fit every size of leg, and it is necessary in 20 some cases, where the upper is a little too small, to leave portions at the top of the upper, disconnected. If the slider is free to move or merely held in adjusted positions by frictional engagement, the movement of the 25 muscles of the foot and leg tends to work the slider along the fastening elements, and the connected parts thus become loose.

The principal objects of my invention are to lock the operating member of a 30 fastening device of the above mentioned character at any point throughout its range of adjustment; to interlock the slider with the elements of the fastener so as to positively hold the operating member against 35 sliding movement therealong; to provide a locking device which is automatically released by adjustment of the slider; to provide an operating member or grip for adjusting the slider which serves to control the 40 locking of the slider and fastener elements; to provide the slider with a finger grip which is hinged thereto and serves when 45 swung outwardly to the proper position for conveniently adjusting the slider, to release 50 the mechanism, and when swung downwardly to the relaxed position, permits the locking device to hold the slider in the ad-

justed position; and in general, to afford a simple, convenient and effective locking device for operating members of quick oper- 55 ating fasteners.

On the drawings:

Fig. 1 is a perspective view of an overshoe having an operating member or slider embodying my improvements; 60

Fig. 2 is an enlarged front view of the slider, with portions broken away and showing portions of the fastener elements which are interlocked and released by the slider; 65

Fig. 3 is a sectional view on the line 3—3 of Fig. 2;

Fig. 4 is a sectional view on the line 4—4 of Fig. 2, showing the locking device in the locking position;

Fig. 5 is a similar view, showing the locking device in the released position; and 70

Fig. 6 is a perspective view of the locking member.

Referring to the drawings, the reference numeral 1 indicates an overshoe as a whole, 75 which has the two side portions 2 and 3 of the upper separated down the front in the usual manner, and provided respectively with a series of interlocking elements 4 and 5 along their edges, which are adapted to be 80 interlocked and released by movement of a slider 6 therealong.

The interlocking elements 4 and 5 are similar to those shown in my co-pending application, Serial No. 757,321, filed December 85 22, 1924, comprising a plain coiled spring 4 secured to and extending along the edge of the side portion 2, and a coiled spring 5 likewise extending along the edge of and secured to the side portion 3, the latter spring 90 having the coils formed with wave-like bends, which interlock with the coils of the element 4 when the outer extremities of the coils of one of the springs are inserted between the coils of the other spring. 95

The operating member or slider 6 comprises opposed front and back plates 7 and 8 respectively, of tapered form, which may be joined together by an integral neck 9 if desired, and have a wedge shaped spreading member 10 interposed between the plates 7 and 8, with the divergent faces thereof substantially parallel with the corresponding divergent outer edges of the plates 7 100

and 3. The wedge shaped spreader 10 may be formed in any convenient manner, as for example by inserting a wedge shaped block between the plates 7 and 8, the plates 5 being reinforced against spreading, in any convenient manner, as for example, by a rivet 11. The outer edges of the plates 7 and 8 are inturned as indicated respectively, at 12 and 13, and these, together with 10 the wedge formation 10, afford divergent channels merging into a single channel at the lower end of the slider in which the elements 4 and 5 are confined, said channels being open along their outer sides to admit 15 the edges of the parts 2 and 3, to which the fasteners 4 and 5 are connected. This slider 6, by reason of the angular arrangement of the divergent channels and the merging of the latter into a channel of 20 suitable size to contain the two elements 4 and 5 when interlocked, serves upon movement in one direction, to guide the elements 4 and 5 into meshing relation and interlock same, and upon movement in the other direction, to separate and release the elements 25 4 and 5. The adjoining elements of each series are spaced apart to receive the elements of the other series individually therebetween in a sufficiently closely nested manner so that, when the elements are interlocked, separation of adjoining elements of 30 either series and release of the opposed element from therebetween is prevented by the proximity and cumulative action of neighboring interlocked elements. Movement of 35 the slider 6 however along the elements 4 and 5 causes a progressive separation of adjoining elements, due to the angularity of the divergent channels of the slider and 40 permits the opposed elements 4 and 5 to be readily interlocked and released.

My present invention relates to a device for holding the slider 6 at any point of its adjustment along the elements 4 and 5, and 45 the particular form of interlocking elements are shown and described merely for the purpose of illustration and to afford a complete understanding of the application of my invention, the latter being however capable of and intended for use in connection with any quick operating fastening device and operating member involving the principle of automatically interlocking and releasing series of fastener elements by movement of a slider or operating member therewith.

The locking device for holding the slider 6 in the various positions of adjustment along the members 4 and 5 consists of a 50 bar 14 extending lengthwise over the upper face of the top plate 7 and secured at its upper end to the slider in any convenient manner. When a rivet is employed for connecting the parts of the slider, as 55 for example, the rivet 11, the bar connec-

tion may be conveniently accomplished by passing the rivet through an aperture in the enlarged upper end of said bar. The lower end of the bar 14 is inturned and preferably pointed, as indicated at 15, and 70 this inturned end projects through an aperture 16 near the lower end of the front plate 7, so as to engage between elements of the members 4 and 5 and thereby hold the slider against movement therealong, 75 said bar being sufficiently springy so that it is yieldingly held in the locking position and adapted to have the lower end swung outwardly to release the point 15 from its engagement with the interlocking element. 80

In connection with sliders of this character, it is customary to provide a finger grip which is usually in the form of a small plate or ring, which is hinged to the slider so that it normally hangs downwardly as 85 shown at 17 in Figs. 1, 2 and 4, and is lifted by the operator to an outstanding position and gripped between the fingers to adjust the slider. I make use of this finger grip 17 and the practice of lifting the finger grip 90 to the outstanding position to control the locking device somewhat automatically, and to this end the bar 14 is formed with an arched portion 18, which is engaged through the aperture 19 of the finger grip 17 and 95 serves to afford a pivotal attachment of the finger grip 17 to the slider. The portion 20 of the finger grip 17 within the arch 18 is of suitable width and form, and the arch 18 also suitably formed so that when the finger grip 17 is swung to the outstanding 100 position shown in Fig. 5, the portion 20 bears against the outer surface of the plate 7 and slides against the inner surface of the arch 18 and acts as a cam to swing the lower 105 portion of the bar 14 away from the plate 7 and lift the point 15 out of its locking engagement with the elements 4 and 5. The rear edge of the portion 20 is preferably 110 flat so that when it is butted against the outer surface of the plate 7, it serves to hold the finger grip 17 substantially perpendicular to this plate 7, and for the purpose of further preventing movement of the finger grip 17 upwardly beyond the perpendicular 115 position, the bar 14 is formed with an enlarged shoulder 21 serving as a stop against which the finger grip 17 contacts when in the position extending outwardly from the face of the plate 7. With this construction 120 the finger grip 17 is locked sufficiently securely in the outstretched position so as to afford a leverage which permits tilting and guiding of the slider by means of the finger grip in locking and releasing the fastener. 125 When the finger grip 17 is turned downwardly to the normal position shown in Figs. 1, 2 and 4, the portion 20 lies substantially flat between the arched portion 18 of the bar and the outer face of the plate 7, so 130

that the bar 14 is free to return to the normal position under its spring tension and the point 15 is re-engaged with the fastener elements 4 and 5.

5 As stated hereinbefore, in operating the slider, it is the practice to lift the finger grip 17 to an outstanding position, and this operation in the present device, serves to automatically release the lock so that the 10 slider is capable of movement, and when the finger grip is released and turned down, the slider is automatically locked in the position to which it has been adjusted.

While the point 15 in the illustrated structure is located substantially midway between the series of locking elements 4 and 5 and interlocks therewith at the point of intermeshing, it is to be understood that the interlocking point may, if desired, be located 20 at one side of the intersection of the two members 4 and 5, so as to interlock with only one of the elements 4 and 5, or it may be arranged to interlock with both at opposite sides of their intersection.

25 This invention is particularly useful in connection with footwear such for example, as overshoes, as it sometimes occurs that the upper is not sufficiently large to close together around the leg, and in such case the 30 slider may be adjusted so as to close the two sides of the upper together as far as this can be conveniently or comfortably done, and the portions therebeyond are left unconnected. In view of the working of the 35 muscles of the leg, the slider has a tendency to work downwardly from the adjusted position unless it is locked at such point. This device insures a positive and convenient means for locking the slider at the upper 40 extremity of its movement or at any point of adjustment along the interlocking members 4 and 5.

In connection with this device I preferably provide the overshoe with a flap 22, 45 preferably of elastic material, which is attached to one side of the upper and has a detachable connection 23 with the other side of the upper, and several spaced connector parts 24 may be provided on the one 50 side of the upper to permit proper connection of the flap 22 when the two sides of the upper are closed together or separated to some extent. With this arrangement, when the slider is run part way up as shown 55 in Fig. 1, the disconnected portions of the upper therebeyond may be neatly held against the leg by the flap 22. Overshoes of this character are usually provided with a tongue at the inside, lying between the two 60 side portions 2 and 3; and this tongue, shown at 25, protects the leg at the gap and affords a neat finished appearance.

65 While I have shown and described my invention in a preferred form, I am aware that various changes and modifications may be

made without departing from the principles of my invention, the scope of which is to be determined by the appended claims.

I claim as my invention:

1. The combination with a quick operating 70 fastener comprising opposed series of interlocking elements on the edges of the parts which are to be connected together and an operating member movable along the series of elements for interlocking and releasing 75 same, of a resilient arm fixed at one end to the operating member and having an in-turned tip at the other end extending through an aperture in the operating member so as to engage the interlocking elements and hold the operating member 80 against movement therealong, and a finger grip having a portion thereof interposed between the arm and operating member and serving as a cam to lock and release the locking device. 85

2. The combination of an article comprising separable parts, having opposed series of fastener elements on the edges thereof, an operating member movable along said elements for interlocking and releasing same, locking means for holding the operating member in position to partially close together and fasten the separable parts so as to leave said parts unconnected therebeyond, 95 and a flap detachably and adjustably connecting said parts and overlying the aforesaid unconnected portions thereof. 95

3. The combination with a fastener comprising opposed series of fastener elements 100 and a slider operable therealong for interlocking and releasing same, of a locking member on the slider and a pull device hinged to the locking member and operable to lock and release the latter. 105

4. The combination with a fastener comprising opposed series of fastener elements of a slider operable therealong for interlocking and releasing same, said slider comprising a pair of wings with diverging channels therebetween, means for holding the wings against separation, a locking member secured to said means and a pull device for operating the locking member. 110

5. The combination with a fastener comprising opposed series of fastener elements and a slider operable therealong for interlocking and releasing same, of a locking bar with a centrally arched portion extending lengthwise of the slider, and a pull device 115 engaging the arched portion of the bar and operable to control the locking operation of the latter. 120

6. The combination of an article with 125 separable parts having opposed series of fastener elements on the respective edges thereof, the adjoining elements of each series being so spaced as to receive the elements of the other series individually therebetween and to produce a locking effect by the cumau- 130

lative action of neighboring elements when the elements are interengaged, a slider movable along said opposed series of elements for progressively interlocking and releasing same, locking means on the slider for holding the latter between the ends of the series of fastener elements so as to partially close together and fasten the separable parts and leave said parts unconnected therebeyond and a flap detachably and adjustably connecting said parts and overlying the aforesaid unconnected portions thereof.

7. The combination of an article with separable parts having opposed series of fastener elements on the respective edges thereof, the adjoining elements of each series being so spaced as to receive the elements of the other series individually therebetween and to pro-

duce a locking effect by the cumulative action of neighboring elements when the elements are interengaged, a slider movable along said opposed series of elements for progressively interlocking and releasing same, a pull member pivoted on the slider, locking means on the slider which said locking means is operable by said pull member and engages with fastener elements adjacent to the slider for holding the latter between the ends of the series of fastener elements so as to partially close together and fasten the separable parts and leave said parts unconnected therebeyond and a flap detachably and adjustably connecting said parts and overlying the aforesaid unconnected portions thereof.

GEORGE W. BLAIR.
